LEAD PENCIL OR SIMILAR ARTICLE

Marshall B. Young, Riverdale, N.Y., assignor to Eagle
Pencil Company, a corporation of Delaware

Application December 5, 1955, Serial No. 39,149

Term of patent 14 years

(Cl. D74—24)

Fig. 1 is a side elevational view of a lead pencil showing my new design;

Fig. 2 is a view similar to Fig. 1 axially turned at an angle of about 60°;

Fig. 3 is a cross-sectional view thereof taken along the line 3—3 of Fig. 1; and

Fig. 4 is a fragmentary, perspective view, on enlarged scale, of the cap end thereof.

The dominant feature of my design resides in the rounded end cap with lateral triangular extensions flush with the faces of alternate panels of the hexagonal pencil casing, and each of length more than twice the thickness of the end cap and of base width substantially equal to that of the corresponding panel, all as shown.

I claim:

The ornamental design for a lead pencil or similar article, substantially as shown and described.
